UNITED STATES PATENT OFFICE.

JEFFERSON D. THOMPSON, OF WASHINGTON, DISTRICT OF COLUMBIA.

SKYLIGHT CONSTRUCTION.

1,075,388.

Specification of Letters Patent. Patented Oct. 14, 1913.

Application filed January 18, 1912. Serial No. 671,809.

To all whom it may concern:

Be it known that I, JEFFERSON D. THOMPSON, a citizen of the United States, residing at Washington, in the District of Columbia, 5 have invented new and useful Improvements in Skylight Construction, of which the following is a specification.

This invention relates generally to skylights and glazed roofs, and more particularly to the construction of the astragals 10 which support the plates of glass, they being so constructed as to permit longitudinal expansion and contraction without breaking the glass, or destroying the water tight 15 joints between the astragals and the glass.

The present invention is designed with especial reference to its use in connection with large roofs wherein the sheets of glass overlap in the manner of shingles and the 20 astragals are upheld or carried on metal or concrete supports or purlins running transversely of the astragals, and connected yielding thereto in such manner that any deflection of the roof from a plane, due 25 to unequal expansion of the purlins or astragals, or bowing of the purlin either upwardly or downwardly, in whole or in part, will be compensated by the novel formation of the astragals and their attachment to the 30 purlins, thus relieving the glass plates and their joints from all strain, insuring the integrity of the glass and the joints from leaking. Furthermore the astragals are provided with longitudinal gutters which, 35 in connection with suitably placed cross gutters, carry off all water of condensation from the under surface of the glass and any possible leakage from without due to some defect in the parts or carelessness in their 40 erection.

With these and other objects in view the invention consists in the novel construction, combination and arrangement of parts hereinafter described in detail and pointed out 45 in the appended claims, reference being had to the accompanying drawings, in which:—

Figure 1 is a sectional view of a portion of a glazed roof or skylight showing in elevation an astragal section at the eaves of 50 the roof and a portion of the overlapping astragal section next above. Fig. 2 is a sectional view on the line 2—2 of Fig. 1, looking in the direction of the arrows. Fig. 3 is a vertical central longitudinal sectional view through the telescopic ends of two 55 astragal sections enlarged. Fig. 4 is a per-

spective view of opposite ends of two inter-engaging or telescopic astragal sections. Fig. 5 is a view similar to Fig. 1 with the glass plates and cap pieces removed. Fig. 6 60 is a plan view of Fig. 5.

In the drawings, wherein like reference characters are used to designate like parts in all the figures, A indicates a portion of an astragal extending from the ridge to the 65 eaves of a roof and supported at suitable intervals by transverse purlins B of channel, I, or other shape. Each astragal is formed of a plurality of relatively short sections 10 fastened each at its upper end to a purlin 70 by a clip or chair 11, and slidably mounted at its lower end in a similar clip fastened to the next lower purlin B. The lower end of each section 10 projects over or overlaps the upper end of the next lower section sufficiently far to permit contraction of each 75 section without possibility of their endwise separation.

The sections 10 of the astragals are similar to one another and a description of one 80 will serve for all. Each section 10 comprises two members, each member being formed of sheet metal, preferably lead coated steel, bent to shape and rigidly connected to each other. One of said members 12, 85 made of a metal strip, is doubled upon itself centrally and longitudinally into close contact to form an upstanding web 13. At a suitable distance below the fold 13^a, the sides of the folded strip are bent outwardly 90 in opposite directions in a common plane, perpendicular to the web 13, as at 14, and then bent upwardly preferably at obtuse angles to form the outer sides 15 of gutters 16. The other member 17 of the section 10 is also made of a strip of metal centrally and longitudinally bent upon itself 95 to form an open web 18 that fits snugly over the web 13, the two members being rigidly fastened by bolts, screws or rivets 19. A 100 suitable distance below the fold 18^a, the two sides 20 of the member 17 are bent upward in semi-circular shape to form two gutters 21 narrower than the gutters 16 and on a higher plane. Their outer sides, formed by the sides 20, after being carried to a sufficient height are again given semi-circular 105 outward turns to form curved supports or seats 22 for longitudinal glazing cushions or strips 23 of soft metal, as lead. 110

To permit the telescopic connection or overlapping of the upper end of one section

10 by the lower end of the section 10 above it, the web 13 of the upper end of each member 12 is cut entirely away for a sufficient distance from the upper end of the section 10, as is also a portion of the web 18 of the member 17, as clearly shown in Fig. 4. At the lower end of each section 10 the member 17 does not extend to the lower end of the member 12 by a distance 10 equal to the cutaway portion of the web 13 at the upper end. Before the members 12 and 17 of each section are fastened together several screw bolts 24 having pointed ends and elongated heads 25 are passed through 15 holes in the fold 18^a of the member 17 and held in upright position by the elongated heads fitting tightly between the folds 13^a and 18^a, see Figs. 2 and 3.

The clip or chair 11 which holds the upper 20 end of a section 10 has a tongue 26 riveted on the upper surfaces of the parts 14 where the rib 13 is cut away, thereby holding said parts together. A finger 27 projects below the tongue 26 and under a purlin B to which 25 it is fastened by a bolt 28 as indicated. The clip or chair 11 has a flattened surface or seat 29 at a higher elevation than the tongue 26 on which the lower end of the gutters 16 of the next section 10 above rests and slides 30 as the section expands and contracts. To hold the sections in proper relation to each other, an upwardly inclined guide arm 30 extends from each side of the clip close against the outer sides 15 of the gutters 16, 35 said arms terminating each in a hook 31 to loosely embrace the edges of said outer sides 15.

The sections 10 of the astragals A being constructed as described, are ready to be 40 placed in position. Fastened to the eave purlin B, which in this instance is a channel bar, are clips or chairs 11^a similar to the clips or chairs 11 spaced the desired distance apart. A section 10 is then inserted in each 45 clip 11^a from above, and slides downward until the clip 11 on the upper end of the section catches by its finger 27 the purlin B next above the eave purlin. Tightening of the bolt 28 fastens the section 10 in place. 50 The sections 10 next above have their lower ends slid into the fixed chair or clips 11 on the sections below, until like chairs 11 on the upper ends of the upper sections engage another purlin B to which they are 55 fastened by the bolts 28. This assembling of sections is continued until the astragals, parallel to one another, are completed from eaves to ridge of roof. It is to be noted that the seat 29 on the chair 11 over which 60 the gutters 16 of each section 10 slides is so placed as to raise said gutters above similar gutters of the section below; furthermore, as the gutters slide downwardly over the clip into place, the web 13 of the member 12 of the same section passes between

the cut down sides 20 of the open web 18 of the section below. These slip joints or telescopic connections between the sections throughout the length of an astragal permit longitudinal movement of the free end of each section due to temperature and other causes, and, as the gutters of the higher sections overlie those of the lower section for some distance, water of condensation will always be carried to the eaves and none will be permitted to leak over the fixed end of the sections. 70

The lower or eave sections 10 differ slightly from the other sections by having the lower ends of its members 17 coincident with the like ends of the members 12, see 80 Fig. 1. These ends project over the eave purlin B and are closed by a cross plate 32 carrying a cross gutter 33 beneath the outer ends of the sections 10 into which flows the 85 water of condensation from the section gutters 16 and 21. The cross gutter 33 has perforations 34 in its bottom for the escape of water. The upper edge of the cross plate 32 is folded inwardly to form a downwardly 90 flanged shelf 35 and a stop 36 for a purpose presently to be described.

After erecting the astragals A, or while erecting them and as quickly as lateral aligned sections are secured to the purlins, 95 soft metal cushions or strips 23 are placed on the curved supports 22 to receive the plates of glass 37 of a length equal to the sections 10 and about as wide as the distance between the webs 18 of laterally adjacent 100 sections. The side edges of the glass plates extend beyond the cushions or glazing strips 23 nearly to the webs 18 and over the gutters 21, so that any water dropping from these edges will be caught in gutters and carried off. 105

Before placing the glass plates in position a pair of cross gutters 38 formed on the side edges of a flat strip 39 having an upstanding flange 40 is first placed on the glazing 110 strips below the upper end of the glass plate. The cross gutters 38 are sufficiently long to project at their ends over the gutters 16 and drain into them any water of condensation or leakage received by the cross gutters. The strip 39 and its flange 40 project beyond the ends of the cross gutters and lie on the glazing strips, as shown in Figs. 2 and 6. After positioning the cross gutters, the glass plate 37 is put in place 115 with its upper edge against the flange and sufficient pressure applied to the glass which forces the ends of the strips 39 into the sharp edges of the soft cushion 23 and seats the glass water tight on said sharp edges. 120

After setting the first glass or the first row of glass plates which are the lowermost or nearest eaves, and which are prevented from sliding down the soft metal cushions or glazing strips 23 and off the roof by the 130

shelves 35 and the stops 36, the next row of glass plates will then be set in position. Because the lower ends of the sections 10 next above overlap the upper ends of the lower sections and are in a higher position, the lower ends of the glass plates carried by these upper sections, which are of the same length as said sections, overlap the lower glass plates, leaving spaces therebetween, which space between each pair of plates is closed against the entrance of rain by spring metal packing 41 forming part of a supporting member 42 for the lower end of the upper glass.

15 The supporting member and spring packing is preferably made of a strip of thin sheet metal having sufficient resiliency for the purpose and of a length about equal to the distance between two webs 13. The resilient sheet is doubled sharply upon itself from end to end, after which the folded edge is turned at a right angle to the support 42 to form a stop 43 that prevents the glass slipping downward. The free edges 25 of the supporting member are folded under said member to form the two spring packing tongues 41, one in advance of the other, which extend from one edge of the glass to the other, and upon pressing upon the upper 30 surface of the lower glass prevent rain entering between the plates of glass. The supporting members 42 are positioned and carried to hold in proper relation the associated glass plates, by brackets 44 riveted on 35 opposite sides of each web 13 at its extreme lower end, a suitable distance below its fold 13^a. Each bracket 44 is here shown as made of sheet metal folded in such manner that two thicknesses lie against the web 13 and are 40 riveted thereto, one thickness projecting outwardly from the web to form a flat shelf 45 on which is placed one end of a supporting member 42, while from the lower edge of the shelf in line with the end of the web 13 45 is an upstanding flange 46 against which the stop 43 of the supporting member rests.

After the plates of glass 37 have been placed in position and supported as described, they are held in place by cap-pieces 50 47 straddling the webs 13 and 17 from end to end and fastened by nuts 48 screwed on the bolts 24 which pass through openings in the top of the cap pieces. The cap pieces are made of sheet metal, bent into shape 55 with flat tops and straight spreading sides, the lower edge of each side having attached thereto a strip of thin soft metal 49, as lead, which is pressed flat on the glass, as clearly shown in Figs. 1 and 2, and forms a tight 60 packing which prevents water running under the cap and around the side edges of the glass. Each cap-piece, except those at the eaves, projects a short distance beyond the lower edges of the glass plates which it 65 overlies, and is closed at its exposed end by

folding the metal forming the cap-piece perpendicular to its sides, see Fig. 2, and, if desired, soldering the folded portions. The lead strips 49 which project beyond the glass are bent downwardly, approximately perpendicular, and contact with the lead strips projecting from the underlying cap-piece. An end clip 50 is riveted or otherwise fastened to the lower end of each cap-piece at the eaves of the roof, which projects downwardly over the cross plate 32 and assists in holding the same in position against the strain of the plates of glass supported on the shelf 35 forming a part of said plate.

A glazed roof or skylight constructed as above described is a great improvement over all similar structures heretofore known, in that its flexibility is such that the parts readily yield under all strains to which they may be subjected without effecting its stability, breaking the glass, opening joints, and leaking, nor permit water of condensation to fall on the floor or run down the walls. By forming the astragals in sections, telescopically or slidably connected by loose joints only, expansion and contraction of the astragals, which sometimes are quite long, is in each instance divided between a number of relatively short sections, the molecular movement of each of which sections 95 under varying temperatures is comparatively short. The telescopic connections between the astragal sections are purposely made loose or free to permit independent movement of the sections with respect to one another should the purlins arch or bend from temperature or other causes, settling of the walls of the building and other strains placed upon the astragals. All movements of the section will take place without straining the joints because of the loose connection of one section with another. No strain is placed on the glass because each plate of glass is supported at its side edges on soft metal cushions or glazing strips carried on 100 flexible portions of never more than two sections laterally in line, and held on said cushions by individual flexible caps bearing on the glass immediately over the cushions, packing strips, preferably of soft metal, being interposed between the glass and the bearing edges of the caps. The upper and lower ends of each glass plate rest on cross strips carried by the same sections that support the glass. There being no rigid connections between any plate of glass and its metal supports, slight movements of the latter may take place without straining said glass. Neither can there be any strain on the glass when the sections move relatively 105 to one another as there is no contact between one plate of glass and another. The nearest approach is where one plate at its lower end overlaps the upper end of the next plate below and here they are separated by a pack- 110

115

120

125

130

ing that forms primarily, a means for preventing rain being driven between the overlapping ends of the plates of glass. As this packing is a resilient one, the space between the glass plates will remain closed whether the plates of glass are separated or brought closer together.

Leakage is prevented at the ends of the plates of glass by the soft metal packing on the cap-pieces which lies some distance within the edges of the plates and hugs closely to the surfaces thereof. Should however any water pass under the packing it would drop from the edge or edges of the glass into the gutters 21 of the sections and run down them into the cross gutters 33 at the eaves.

The cross strips 39 which support the upper ends of the plates of glass have a gutter on each edge, parallel with the strips, their ends projecting over the gutters 16 of the sections 10 below the gutters 21. Any water of condensation running down the undersides of the glass plates will be caught by these cross gutters and conveyed to the longitudinal gutters 16 to be emptied into the cross gutter 33.

I claim:—

1. In a sky-light construction, the combination with a plurality of purlins, of a plurality of astragals supported on said purlins, each astragal being formed of a number of sections fastened at their upper ends each to a purlin and slidably freely at their lower end within the upper ends of the sections below.

2. In a skylight construction, the combination with a plurality of purlins, of a plurality of astragals supported on said purlins, each astragal being formed of a number of sections fastened at their upper ends each to a purlin and slidably freely at their lower ends within the upper ends of the sections below, and chairs or clips secured to the upper ends of the sections and to the purlins, each chair in position to support the free slidable end of an astragal section.

3. In a skylight construction, the combination with a plurality of purlins, of a plurality of astragals supported on said purlins, each astragal being formed of a number of sections each slidable freely at their lower ends within the upper ends of the sections below, a chair or clip fixed on the upper end of each section having a seat supporting the free end of the section above, and means for fastening the chairs to the purlins.

4. In a skylight construction, the combination with a plurality of purlins, of a plurality of astragals supported upon said purlins, each astragal comprising a plurality of overlapping independently movable sections, and a clip or chair secured on one end

of each section and fastened to a purlin, 65 each chair having a seat for the free overlapping end of the adjacent section.

5. In a skylight construction, the combination of a plurality of purlins, of a plurality of astragals supported on said purlins, each astragal comprising a number of overlapping independently movable sections, a clip or chair secured on the upper end of each section and fastened to a purlin, each chair having a seat within which 75 the free lower end of the overlapping section may slide longitudinally and rock in a vertical plane, plates of glass each yieldingly supported at its side edges by a section of adjacent astragals and free to move 80 and rock with said sections independently of other sections and plates, and means for holding the plates on the supporting sections.

6. An astragal for skylights constructed 85 of a plurality of flexibly connected sections overlapping one another at their ends, and a clip or chair on the upper end of each section for rigidly connecting said end to a fixed part of a structure to be covered, said 90 chair having a seat to slidably support the free overlapping end of the section above.

7. An astragal for skylights constructed of a plurality of overlapping sections, and means secured on the upper end of each section by which it is rigidly connected to a fixed part of a structure to be covered, said 95 means each having a seat to slidably support the lower free overlapping end of a section next above.

8. An astragal for skylights constructed of a plurality of flexibly connected overlapping sections, and a clip or chair secured to the upper end of each section for rigidly connecting said end to a fixed part of a 105 structure to be covered, said clips or chairs each having an elevated guide or seat to slidably support the lower free end of an overlapping section above the fixed end of the section next below.

9. An astragal for skylights constructed of a plurality of flexibly connected sections, each section comprising an upper member and a lower member, each made of resilient sheet metal with a central web and a gutter 115 on each side of the same, said webs being interconnected, the gutters on each upper member forming yielding supports each for one edge of a separate skylight glass, and a clip or chair having an elevated guide attached to the upper end of each lower member of a section for rigidly securing said section at one end only to a fixed part, the opposite free end of said lower member being slidably supported on the elevated guide 120 of the clip or chair holding the section next below and overlapping the lower member of said section.

10. Astragals for skylights each constructed of a plurality of flexibly connected overlapping sections, each section comprising an upper member and a lower member made of resilient sheet metal with a central web and a gutter on each side of the same, said webs being interconnected and fastened together, the facing upper gutters of coördinate sections of two astragals forming yielding supports for the sides of a skylight glass, and a clip or chair attached to the upper end of each section to secure the same to some fixed part, said clips or chairs each having a seat to support the free lower end of the section next above, whereby each section and the glass plate supported thereon may move independently of other sections and glass plates.
11. An astragal for skylights constructed of a plurality of sections fixed at their upper ends and at their movable lower ends overlapping the fixed ends of the sections next below, each section comprising an upper member and a lower member each having a central web and a gutter on each side of the same, said webs being interengaged and fastened together, the facing upper gutters of coördinate sections of two astragals forming yielding supports for the side edges of a skylight glass, the lower member of each section projecting beyond the upper member at one end and having a shorter web at the opposite end, a bracket on each side of the projecting web of the lower member at its end, a support for the lower edge of the skylight glass carried by said brackets and a clip or chair fastened to the lower member at its upper end for connecting said section to a fixed part, said clip or chair having an elevated guide for the end of the overlapping section.
12. An astragal for skylights constructed of a plurality of sections fixed at their upper ends, their lower movable ends overlapping the fixed ends of the sections next below, means on each section for supporting the side edges of two plates of glass overlapping but disconnected from like plates of glass supported by the sections next below, spring packing between the overlapping plates of glass, and a bracket on both sides of the lower end of each section for supporting the ends of the spring packing.
13. An astragal for skylights comprising a plurality of sections, and a clip or chair secured on one end of each section having means for rigidly connecting it to a fixed part of a roof and provided with a seat for the overlapping free end of another section adapted to slide longitudinally therein and rock vertically with relation thereto.
14. An astragal for skylights comprising a plurality of overlapping sections, means secured on the upper end of each section for rigidly fastening said end to a fixed support, and having a seat on which the free overlapping lower end of the section next above may slide and rock, and means on each section for supporting one edge of a pair of glazing plates.
15. In a sectional astragal for skylights, means for immovably securing one end of each section, said means comprising a clip rigidly fastened to one end of each section, and having a finger for securing the clip to a fixed part, an elevated support, and an arm projecting above each end of said support terminating in a hook.
16. A glazed structure comprising an astragal made of a plurality of telescopically connected sections, a supporting medium for each end of each section, a pane of glass on each section and a cap on each pane of glass, said sections each having telescopic engagement at one end with a supporting medium.
17. A glazed structure comprising an astragal made of a plurality of telescopically connected sections, supporting mediums for said sections at their opposite ends, a pane of glass on each section, and a cap on each pane of glass, each section being firmly attached to one of its supporting mediums and telescopically engaging the other.
18. A glazed structure comprising an astragal made of a plurality of telescopically connected sections, each section being supported for free response longitudinally to varying temperatures, means for checking displacement of said sections downwardly along the pitch of the general structure, a pane of glass on each section, and a cap on each pane of glass.
19. A glazed structure comprising rigid frame-work, an astragal made of a plurality of overlapping slidably connected sections, a supporting medium firmly attached to a corresponding end of each section and to said frame-work and provided with a seat for the opposite sliding end of the adjacent overlapping section, a pane of glass on each section, and a cap on each pane of glass.
- In testimony whereof I have hereunto set my hand in presence of two subscribing witnesses.
